(57) **CLAIM**

The ornamental design for a “railcar beam,” as shown and described.

DESCRIPTION

FIG. 1 is a perspective view of an embodiment of a railcar beam, according to the principles of the present invention.

FIG. 2 is a plan view of the embodiment of FIG. 1.

FIG. 3 is a bottom view of the embodiment of FIG. 1.

FIG. 4 is an end view of the embodiment of FIG. 1.

FIG. 5 is the other end view of the embodiment of FIG. 1.

FIG. 6 is a rear view of the embodiment of FIG. 1; and, FIG. 7 is a perspective view of the embodiment of FIG. 1 with removable brake heads shown in phantom.

The broken line showing of brake heads is for illustrative purposes only and forms no part of the claimed design.
